UNITED STATES PATENT OFFICE.

MICHAEL R. DALEY, OF FALL RIVER, MASSACHUSETTS.

SAFETY MONEY-DRAWER.

SPECIFICATION forming part of Letters Patent No. 528,082, dated October 23, 1894.

Application filed November 11, 1893. Serial No. 490,656. (No model.)

To all whom it may concern:

Be it known that I, MICHAEL R. DALEY, a citizen of the United States, residing at Fall River, in the county of Bristol and State of Massachusetts, have invented certain new and useful Improvements in Safety Money-Drawers, and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to money tills, and its object is to prevent mistakes in making change, and to detect any attempt on the part of a purchaser to make the tradesman believe that a bill of a larger denomination has been given him, than that actually handed in.

The invention is applicable to any compartment till, but especially to the well known Miles alarm till, which is the one shown in the accompanying drawings, in which—

25 Figure 1 is a perspective view of the till, with the change tray broken away. Fig. 2, is a top plan view with the change tray removed. Fig. 3, is an elevation, partly in section, of the rear side of a part of the compartments. 30 Fig. 4, is a perspective view of the right hand front corner, partly broken away. Fig. 5, is a perspective view of one of the movable covers. Fig. 6, is a detail.

The front part of the till A, is divided into 35 four compartments, 1, 2, 3, 4, each of a suitable length and width to hold a bank bill or a Treasury note. Compartment 1 is for one-dollar bills; compartment 2, for two-dollar bills; compartment 3, for five-dollar bills; and 40 compartment 4, for ten-dollar bills, and those of higher denominations. Above these compartments is a tray B, containing pockets for small change. The tray rests upon and slides on shoulders *a* on the inside of the till, so that 45 it can be brought forward to cover the bill compartments, or slide back to uncover them. At the back of the till is the alarm lock C. All these parts are of the usual construction and form no part of my invention.

50 To accomplish the objects above set forth, I place over the four bill compartments, three separate movable covers D, D', D'', each of the

right size to cover one compartment. These covers are suitably arranged in guides to slide to one side or the other; as for instance, by 55 providing them on the under side with eyes *d* which engage with one or more rods or stout wires E running transverse to the compartments, and fixed at each end in the sides of the till. These three covers, it will be seen, 60 always leave one compartment open, and this may be any one desired by merely shifting the covers to one side or the other. In the drawings, compartment 3 is left open, disclosing a five-dollar bill therein. Should it be 65 wished to get out a two-dollar bill cover D' can be slid to the right, covering compartment 3 and opening compartment 2.

In making change for a one-dollar bill, compartments 2, 3, and 4 will be covered, while 70 compartment 1, into which the bill has been placed, will remain open, the change being taken from the tray; but suppose a two-, five- or ten-dollar bill is given, and it is desired to get bills of a lower denomination to give in 75 change. The fundamental principle for operating the invention, is to leave open the compartment into which has been placed the given bill, so as to have it always in sight until the transaction is completed. In order to accomplish 80 this end, and yet give access to the compartments, each cover is made with a removable lid. This may be arranged in any suitable manner, but I prefer to make it as a slide *d'* running in grooves in the frame *d²* of the 85 cover, and adapted to move lengthwise of the compartment. The slide may have a rib or other handle *d³* by which to move it, and at the front end is preferably an upright lip or flange *d⁴*, to be engaged by the change tray 90 when the latter is pulled forward, and so close the lid or lids which may have been opened. Guides G keep the lids in line with the covers when slid back, and blocks H support the lids on a level with the frames. These 95 lids give access to the compartments without moving the covers, so that change for a large bill may be obtained without covering the compartment in which said bill has been placed; but to prevent mistakes, it is necessary to provide some means for preventing the tradesman from opening the lid of a compartment containing a larger bill than the one he is making change for, and yet give

free access to the compartments holding lower bills. This is accomplished by providing compartments 2, 3, and 4 with a lock which prevents the lids from being opened when the cover has been moved over them from left to right, but does not fasten them when the cover has been moved from right to left. I prefer to use the lock shown in the drawings, in which a short rock shaft F is journaled in a hole in the rear wall of each of the compartments 2, and 3. On the front end of each rock shaft is a rock arm f. On the rear end is an oppositely disposed weighted arm f', and a short arm f² nearly at right angles thereto. The rock shaft stands normally with the arms f f' vertical, as shown in Fig. 1; but when a cover is moved from left to right, the rear end of the cover, or preferably a tongue d⁵ thereon, strikes the arm f and turns it down to the right, thereby raising the weighted arm f' and bringing up the intermediate arm f² into an upright position, as shown in Fig. 3, so that it stands just behind the rear edge of the lid, and prevents it from being slid back. On the other hand, when cover D', for instance, is moved from right to left, from compartment 3 to compartment 2, its tongue d⁵ turns the arm f down to the left and the arm f² is carried still farther down, as shown in Fig. 1, so that there is nothing to prevent the lid being slid back to open compartment 2. The stop at the rear of compartment 4 may be a permanent one F' as shown, while no stop at all is needed at the rear of compartment 1. From this construction it results that all the lids to the right of an open compartment are locked, while those to the left are free to be opened. In making change, therefore, bills can only be taken from compartments holding lower denominations than the bill which has been given in, and which lies in the open compartment.

The invention is applicable to the change tray, as well as to the bill compartments, but for the sake of simplicity only the latter have been shown as equipped with the covers.

Having thus described my invention, what

I claim is—

1. The combination with a money till provided with compartments, of separate covers therefor, movable both laterally and longitudinally to uncover said compartments, substantially as described.
2. The combination with a money till provided with compartments, arranged side by side, of a separate cover for each compartment save one, said covers being laterally and longitudinally movable over said compartments, substantially as described.
3. The combination with a money till provided with compartments arranged side by side, of a series of separate covers therefor,

one less in number than said compartments and movable both longitudinally and laterally over said compartments, and one or more guides for directing the lateral movement of said covers, substantially as described.

4. The combination with a money till provided with compartments, of a series of covers therefor, one less in number than said compartments, and laterally movable over the same, and suitable locking devices adapted to prevent said covers from being opened when moved to the right, and to permit their free opening when moved to the left, substantially as described.

5. The combination with a money till provided with compartments, of a series of laterally movable covers therefor, and a lid in each cover, substantially as described.

6. The combination with a money till provided with compartments, of a series of laterally movable covers therefor, and a slide in each cover adapted to move lengthwise of the compartments, substantially as described.

7. The combination with a money till provided with compartments, of laterally movable covers for all but one of said compartments, each cover consisting of a grooved frame, and a lid sliding in the grooves lengthwise of the compartment, substantially as described.

8. The combination with a money till provided with compartments, of laterally movable covers for all but one of said compartments, a movable lid in each cover, and means for locking all the lids on one side of the open compartment, and unlocking all the lids on the other side thereof, substantially as described.

9. The combination with a money till provided with compartments, of laterally movable covers for all but one of said compartments, a longitudinally movable lid in each cover, and a locking device at the rear of one or more compartments consisting of a rock shaft having two oppositely disposed arms, and an intermediate arm, substantially as described.

10. The combination with a money till provided with compartments, and a sliding change tray above the same, of laterally movable covers for the compartments, a longitudinally sliding lid in each cover, and a lip on each lid to be engaged by the tray when it is pulled forward, substantially as described.

In testimony whereof I affix my signature in presence of two witnesses.

MICHAEL R. DALEY.
